RAILWAY TRAFFIC CONTROLLING
APPARATUS

Leslie R. Allison, Forest Hills, Pa., assignor to The
Union Switch & Signal Company, Swissvale,
Pa., a corporation of Pennsylvania

Application April 26, 1941, Serial No. 390,609

6 Claims. (Cl. 246—63)

My invention relates to railway traffic controlling apparatus, and it has particular reference to apparatus of the type employed in railway signal systems wherein coded track circuit energy is employed to effect control of either or both wayside signals and train-carried traffic controlling devices such as cab signals and train control apparatus. More particularly, my invention relates to decoding apparatus employed in such systems for decoding coded track circuit energy.

In coded systems of railway signaling, energy coded or periodically interrupted at one or another of a plurality of code rates of the frequency code type comprising recurrent cycles each consisting of one "on" and one "off" interval during which energy does and does not flow, respectively, is transmitted through the track rails to cause operation of a code following relay device which may, for example, be of the tractive armature; saturable core; or electronic tube type. In such a system, the rate of operation of the code following relay is detected by means of decoding apparatus including circuits tuned to resonance at one or another of a plurality of code rates and supplied with energy from a decoding transformer. The decoding transformer is supplied with unidirectional current during each "on" and "off" interval of the track circuit current, in such manner as to reverse the direction of flux in the decoding transformer at a rate corresponding to the rate of operation of the code following relay. This reversal of flux in the decoding transformer causes the induction in the transformer of an alternating electromotive force having a frequency corresponding to the rate of flux reversal.

The tuned circuits supplied with energy from the decoding transformer are tuned to resonance at frequencies corresponding to one or another of the code rates employed. In systems now commonly in use, code rates of 75, 120 and 180 cycles per minute are employed, and the decoding apparatus is arranged to detect 75 code by means of an untuned circuit and the 120 and the 180 codes by means of tuned circuits selectively responsive to one or the other of the desired code rates. The selectivity of these tuned circuits of course varies in accordance with the frequency of current supplied thereto, with the result that certain harmonics of the low (75) code rate might fall within the range where the tuned circuits are less selective. Similarly, harmonics of the intermediate (120) code rate might be objectionable from the standpoint of the selectivity of the circuits.

The decoding apparatus employed in railway

signal systems is required to meet certain specified standards based upon safety of operation, size, weight, shape, and other factors. These limitations make it essential that the size and 5 the weight of the apparatus be kept always at a minimum, thereby limiting the size of the magnetic core structure employed in the decoding transformer and tuning reactors. As a result, therefore, the apparatus must be designed around 10 a given size core structure with the windings and tuning apparatus proportioned with respect to the core. The inductance to resistance ratio of the windings of the decoding transformer is, therefore, limited since a relatively high ratio 15 results in early saturation of the core due to the ampere turns available. To avoid such saturation, a lower ratio of inductance to resistance is employed, and as a result the energy supplied to the transformer has a substantially square-cornered wave form, and the variations of flux in the transformer have a similar form. At the 75 code rate, and to some extent also at the 120 code rate, the electromotive forces induced in the transformer comprises sharply peaked impulses 20 separated by intervals when little or no voltage is induced. In the tuned circuits, these impulses act as though comprised of a fundamental frequency rich in harmonics. The harmonic portion of such voltages, lying within the less selective 25 portions of the resonant curves of the tuned circuits, causes a current to flow therein relatively higher in magnitude than that due to the fundamental frequency of the low code rate. This then decreases to a considerable extent the selectivity 30 of the circuits, and might lower the margin of safety of the circuits to a large extent.

With the size of the core limited, and with restrictions placed upon the inductance-resistance ratio of the windings, other means must be devised to vary the wave form of flux in the transformer so as to approximate more closely a sinusoidal wave form to which the tuned circuits are most selective. An object of my invention is the provision of decoding apparatus incorporating 40 novel and improved means for obtaining an output voltage wave substantially sinusoidal in form and having relatively low harmonic components.

Another object is to provide decoding apparatus arranged to delay the growth and decay of 45 flux in a decoding transformer whereby to cause the resultant induced voltage to have relatively low harmonic components.

A further object is to provide decoding apparatus meeting all the requirements of railway signaling as to size, shape, weight, etc., and incor-

porating novel and improved means for increasing the selectivity of the tuned circuits forming a part thereof.

The above-mentioned and other important objects and characteristic features of my invention which will become readily apparent from the following description, are attained in accordance with my invention by incorporating into the decoding apparatus reactance devices so arranged as to delay the growth and decay of flux in the decoding transformer, or in other words, to increase the time constant of the circuit which includes the primary winding of the decoding transformer. This reactance unit may take the form of a copper ferrule, or a short-circuited winding mounted on the transformer core.

I shall describe one form of apparatus embodying my invention, and shall then point out the novel features thereof in claims.

In the accompanying drawing, Fig. 1 is a diagrammatic view illustrating a preferred form and arrangement of apparatus embodying my invention. Fig. 2 is a graph in which the time rate of change of flux in an ordinary decoding transformer and a decoding transformer constructed in accordance with my invention are represented by curves *a* and *b*, respectively. Fig. 3 is another graph representing the resultant induced voltages in the transformers. Fig. 4 is a graphical representation of the selectivity curves of decoding apparatus constructed in accordance with the usual practice and also in accordance with my present invention.

In the particular embodiment of my invention illustrated in Fig. 1, apparatus embodying my invention is shown applied to a four-indication cab signal system wherein selective control of a train-carried cab signal is established in accordance with the rate at which energy inductively received from the rails of a trackway is coded. Referring now to Fig. 1, the reference characters *1* and *1a* designate the track rails of a stretch of trackway, the rails of which are supplied with track circuit energy coded at one or another of the customary plurality of code rates. The wayside apparatus which supplies coded energy to the rails *1* and *1a* is not shown in the drawing, since it forms no part of my present invention, but such apparatus may take any one of the well-known forms employed in what is known as three block, four-indication frequency code signal systems, effective to supply the rails of the trackway with energy which is coded at one or another of three different rates of coding in accordance with traffic conditions in advance. For the purposes of this description, I shall assume that the rails *1* and *1a* are supplied by such wayside apparatus with alternating trackway energy which is coded or periodically interrupted at a rate of 75, 120 or 180 times per minute. In accordance with the usual practice, I shall assume that the wayside apparatus is controlled by traffic conditions in advance so that the highest or 180 code rate is supplied to the rails *1* and *1a* under clear traffic conditions on the stretch; that the intermediate or 120 code is supplied under approach medium traffic conditions; and that the lowest or 75 code is supplied under approach traffic conditions.

The trackway energy supplied to the rails *1* and *1a* is inductively picked up by the usual two receiving coils *4* and *5*, which coils are carried on the locomotive in front of its first pair of wheels and which are connected together in series in such manner that when electromotive forces are

induced therein in response to alternating currents of opposite instantaneous polarities in the rails *1* and *1a*, such forces are additive. The two coils *4* and *5* are connected through the medium of the usual amplifier AM to a master code following relay MR.

The reference characters L, R and A designate decoding relays for detecting the rate of operation of code following relay MR, and which decoding relays may be utilized as shown for controlling a train governing device such as a cab signal CS. In accordance with the usual custom, the apparatus is arranged so that when relay A is energized, lamp *8* of signal CS is illuminated to indicate a clear traffic condition; when relay A is released and relay R is picked up, lamp *9* is illuminated to indicate an approach medium traffic condition; when relays A and R are released and relay L is picked up, lamp *10* is illuminated to indicate an approach traffic condition; and when relays A, R and L are released, lamp *11* is energized to indicate slow speed.

The decoding relays are selectively controlled by relay MR in accordance with its rate of operation through the medium of decoding apparatus comprising selective circuits and a decoding transformer DT. Transformer DT comprises a magnetizable core upon which are mounted a primary winding *14* and a secondary winding *15*. One terminal C of a suitable source of unidirectional current, such as a battery not shown but having its opposite terminals designated by the reference characters B and C, is connected through a resistor *16* to a mid terminal tap of winding *14*, and the other terminal B of the source is connected to one end or the other of winding *14* according as contact *17* of relay MR is in its attracted front position or is in its released back position, respectively. As shown, a condenser *18* may be connected across winding *14* to suppress sparking at the contacts of relay MR. It follows, therefore, that the flux in the core of transformer DT is reversed at a rate corresponding to the rate of operation of contact *17* of master relay MR.

Relay L is connected through a full-wave rectifier *19* and a reactor *20* to secondary winding *15* of transformer DT, and this relay, as will be made clear presently, is picked up whenever relay MR follows any one of the heretofore mentioned code rates of 75, 120 and 180 cycles per minute.

Relay R is connected through a full-wave rectifier *19* to a secondary winding *21* inductively coupled with a reactor winding *22* connected in series with a capacitor *23* across winding *14* of transformer DT. Relay R, as will be made clear presently, is effectively energized and picked up when relay MR operates at the 120 code rate. The other decoding relay A is connected through a full-wave rectifier *19* to a secondary winding *24* inductively coupled with a reactor winding *25*, which latter winding is connected in series with a capacitor *26* across winding *14* of transformer DT. Relay A is effectively energized and picked up when and only when relay MR operates at the 180 code rate. The parts of the apparatus are proportioned in such manner that the circuit path including capacitor *23* and reactor winding *22* is tuned to resonance at a frequency (2 cycles per second) corresponding to the 120 code rate, while the other circuit path comprising capacitor *26* and reactor winding *25* is tuned to resonance at a frequency (3 cycles per second) corresponding to the 180 code rate.

The apparatus so far described corresponds to that heretofore proposed and such apparatus functions in the following manner. When 75 code energy is inductively received by the coils 4 and 5, relay MR operates at the 75 code rate to cause flux reversals in the transformer DT to occur at a corresponding rate. Due to the heretofore mentioned limitations upon the size of core and inductance-resistance ratio of the transformer, the flux builds up quickly in the core each time contact 17 of relay MR operates from one position to the other. The flux growth in the core of transformer DT at the 75 code rate is represented by curve *a* of Fig. 2, and it is readily apparent from an inspection of this curve that the time (OA) required for the flux to build up to its maximum value is substantially less than either the "on" or "off" interval time (OA') of the 75 code. The resultant voltage induced in transformer winding 15 by this flux variation is represented in curve *a* of Fig. 3, and from an inspection of this curve it is readily apparent that the voltage induced is of relatively short duration and is sharply peaked. Voltage impulses corresponding to those shown in curve *a* of Fig. 3 occur each time contact 17 of relay MR operates from one position to the other, it being understood of course that each two successive impulses have opposite polarities. These impulses are applied from winding 15 through rectifier 19 to relay L in the form of impulses of unidirectional current, and relay L accordingly is energized. The circuit connection of relay L to winding 15 of transformer DT is untuned, hence such relay is energized by voltage impulses occurring at any one of the heretofore assumed code rates of 75, 120 and 180 cycles per minute. At the higher code rates, the spacing between voltage impulses is of course decreased and the energization of the relay L is increased. To avoid overenergizing relay L at the higher code rates, reactor 20 is introduced in the circuit of relay L to limit the applied voltage, and is proportioned so as to maintain substantially constant the energization of relay L irrespective of the code rate of operation of relay MR.

The impulses of voltage induced in transformer DT are applied also to the selective circuits, but since these impulses occur at the 75 code rate and the circuits are tuned at 120 and 180 code rates, respectively, little current flows in the circuits due to the fundamental frequency of the 75 code. However, the separation between impulses permits the harmonic content thereof to cause the resonant circuits to oscillate at their natural periods with the result that an appreciable current flows, as indicated in curve *a* of Fig. 4, wherein the current values caused to be induced in winding 24 are plotted on a logarithmic scale against code rates. Curve *a* of Fig. 4 accordingly represents the energization of relay A at the different code rate of operation of relay MR. Relay R also has an appreciable energization at the 75 code rate due to the harmonic content of the voltage impulses occurring at the 75 code rate.

In accordance with an object of my invention, I modify the decoding apparatus heretofore described by incorporating therein a reactance device effective to reduce the harmonic content of the induced voltages applied from the transformer to the selective circuits. This reactance device may take the form of a copper ferrule mounted on the core of the decoding transformer, or as represented in Fig. 1, the device may be a winding

27 disposed on the transformer core and comprising a relatively few turns of heavy wire, for low resistance. The winding 27 is short-circuited upon itself, and by suitably proportioning winding 27, the time constant of the transformer may be adjusted so as to obtain a delay in both the growth and decay of flux in the transformer and cause the time rate of change of flux to vary substantially as shown in curve *b* of Fig. 2. The voltage induced in winding 15 of the transformer by this rate of flux change has a wave form substantially similar to that represented in curve *b* of Fig. 3, and from an inspection of this curve it is evident that the induced voltage wave contains a much greater proportion of the fundamental frequency of 75 cycles per minute than does the voltage curve *a* of Fig. 3. As a result, an electromotive force is impressed on the resonant circuits throughout substantially the entire code "on" and "off" intervals of the 75 rate, and the circuits accordingly are less free to oscillate at their natural frequencies in response to the harmonic components of the induced voltages. Also, the harmonic components of the induced voltages are reduced and the current available in the tuned circuits at the 75 code rate is thus reduced in magnitude, as can be seen from an inspection of curve *b* of Fig. 4.

The short-circuited winding 27 of the transformer of course absorbs power, and the magnitude of this power is proportional to the frequency. I have found that at the higher rates (120 and 180 cycles per minute) the power absorbed by winding 27 (or its equivalent copper ferrule) tends to offset the increased power available to energize the untuned relay L, with the result that the energization of such relay is maintained substantially constant over the range of code rates employed. This permits reactance 20 interposed in the circuit of relay L to be reduced considerably, thereby effecting a saving in apparatus. Similarly, in case rectifier 19 is eliminated and the untuned relay L is supplied over a contact of master relay MR with substantially unidirectional current from its associated secondary winding 15 in a manner disclosed in United States Letters Patent No. 2,237,788, granted on April 8, 1941, to Frank H. Nicholson and myself and of common ownership herewith, the winding 27 functions to maintain substantially constant the energization of relay L without the use of a reactor.

I have also found that the selectivity of the tuned circuits at their resonant frequencies is substantially unchanged when winding 27 is incorporated into transformer DT. An inspection of curve *b* of Fig. 4 reveals that at the resonant frequency (180 code rate) the current induced in winding 25 and made available in relay A is substantially the same irrespective of whether winding 27 is or is not utilized, but as the code rate decreases, considerably more energy is available when winding 27 is not employed (curve *a*) than is available when the winding is used (curve *b*).

The short-circuited winding 27, or copper ferrule, may thus be considered as giving transformer DT the characteristics of a low pass filter having a cut-off point such that it does not pass the harmonics of the 75 code, corresponding to 225, 375, 525, etc., cycles per minute, to which frequencies the tuned circuits of the A and R relays are readily responsive. It follows, therefore, that I have provided decoding apparatus incorporating novel and improved means for increasing the selectivity of tuned circuits of the type employed

in coded railway signal systems, and have enabled such gain in selectivity to be obtained without increasing the size or weight of the magnetizable core employed in the apparatus.

In addition, apparatus embodying my invention is effective to limit the energization of the untuned relay L and thus maintain substantially constant the energization of the relay over the range of code rates employed. This enables the limiting reactor introduced into the untuned circuit of the 75 code to be greatly reduced or entirely eliminated, thereby reducing the number of elements required in the decoding apparatus.

An additional advantage of apparatus embodying my invention resides in minimizing the possibility of "false clear" failures due to an open-circuit condition in the untuned circuit of relay L. This possibility exists when, as has been the practice heretofore, a relatively large reactor is introduced in the L relay circuit to prevent over-energization of the relay at the higher code rates, since the voltage impressed by the transformer on the circuit must be relatively high in order properly to energize the relay at the low (75) code rate. This of course means that a relatively large proportion of the transformer power is required to operate relay L. The circuit of this relay is not checked, hence should an open-circuit condition exist therein, the energy available at the 75 code rate to energize the tuned circuits of the A and R relays is increased due to the regulation of the transformer, and at the 75 code rate, the current in the tuned circuits might reach a value sufficient to prevent either, or both, the A and R relays from dropping away. Similarly, if the L relay circuit is open at the 120 code rate, relay A might be prevented from dropping away. My invention, by enabling a much smaller reactor to be employed in the untuned circuit of relay L, permits operation of the relay to be obtained with a lower impressed voltage from the transformer and less transformer power. I have found that if the untuned circuit of relay L becomes open-circuited at the 75 code rate, the energy available to energize the tuned circuits of the A and R relays, due to the regulation of the transformer, is much less when apparatus embodying my invention is employed than that available when apparatus of the type heretofore in common use is employed. It follows, therefore, that apparatus embodying my invention minimizes the possibility of "false clear" failures such as might be caused by an open-circuit condition in the untuned circuit of the L relay.

It is, of course, to be understood that although my invention has been described in connection with train-carried apparatus, the invention may be applied equally as well to wayside apparatus incorporating decoding apparatus for decoding coded track circuit energy.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Decoding apparatus for use in railway signal systems having a code following relay responsive to track circuit energy coded at one or another of a plurality of code rates each rate comprising recurrent cycles consisting of alternate "on" and "off" intervals during which en-

ergy is and is not present in the track rails, comprising the combination with said code following relay of a decoding transformer having a magnetizable core provided with a winding supplied by said relay with unidirectional current in such manner as to cause reversals of flux in the transformer at a rate corresponding to the code rate of operation of said relay, selective circuits tuned to resonance at one or another of the plurality of code rates and supplied with energy from a winding of said transformer, and reactive means associated with said transformer for delaying the growth and decay of flux therein to reduce the harmonic components of voltages applied from the winding of said transformer to said selective circuits and thereby improve the selectivity of such circuits.

2. Decoding apparatus for use in railway signal systems having a code following relay responsive to track circuit energy coded at one or another of a plurality of code rates each rate comprising recurrent cycles consisting of alternate "on" and "off" intervals during which energy is and is not present in the track rails, comprising the combination with said code following relay of a decoding transformer having a magnetizable core provided with a winding supplied by said relay with unidirectional current in such manner as to cause reversals of flux in the transformer at a rate corresponding to the code rate of operation of said relay, selective circuits tuned to resonance at one or another of the plurality of code rates and supplied with energy from a winding of said transformer, and a short-circuited winding mounted on said transformer core for delaying the growth and decay of flux therein to reduce the harmonic components of voltages applied from the winding of said transformer to said selective circuits and thereby improve the selectivity of such circuits.

3. Decoding apparatus for use in railway signal systems having a code following relay responsive to track circuit energy coded at one or another of a plurality of code rates each rate comprising recurrent cycles consisting of alternate "on" and "off" intervals during which energy is and is not present in the track rails, comprising the combination with said code following relay of a decoding transformer having a magnetizable core provided with a winding supplied by said relay with unidirectional current in such manner as to cause reversals of flux in the transformer at a rate corresponding to the code rate of operation of said relay, selective circuits tuned to resonance at one or another of the plurality of code rates and supplied with energy from a winding of said transformer, and an inductive means comprising a short-circuited turn mounted on said transformer core for delaying the growth and decay of flux therein to reduce the harmonic components of voltages applied from the winding of said transformer to said selective circuits and thereby improve the selectivity of such circuits.

4. In combination with a code following relay operable by track circuit energy coded at one or another of a plurality of code rates, each rate comprising recurrent cycles consisting of an "on" and an "off" interval during which energy is and is not present, a decoding transformer having a magnetizable core provided with a winding supplied by said relay with unidirectional current flowing therein in one direction during the "on" intervals of code and flowing in the opposite direction during the "off" intervals of code, selective circuits tuned to resonance at one or another

frequency corresponding to one or another of said plurality of code rates, means for supplying said circuits with energy from a winding of said transformer, and a short-circuited turn on said transformer core for increasing the time constant of said transformer to reduce the harmonic content of energy applied from said transformer to said circuits, whereby to increase the selectivity of such circuits.

5. Decoding apparatus for use in railway signal systems having a code following relay operable by track circuit energy coded at 75 and 180 cycles per minute, each cycle comprising an "on" and an "off" interval when energy is and is not present, comprising the combination with said relay of a decoding transformer having a magnetizable core and a winding supplied by said relay with unidirectional current flowing in one direction therein during each "on" interval of a code and flowing in the opposite direction therein during each "off" interval of the code, a selective circuit tuned to resonance at a frequency of three cycles per second and supplied with energy from a winding of said decoding transformer, and a short-circuited turn inductively associated with said first-mentioned winding of said transformer for reducing the harmonic components of the voltages applied from the transformer to said

selective circuit when said relay operates in response to 75 code track circuit energy.

6. In a system for decoding coded track circuit energy of the class wherein a code following relay operated by track circuit energy supplies energy to a decoding transformer for causing alternating current having a frequency corresponding to the code rate of operation of the relay to be supplied to a circuit tuned to resonance at a frequency corresponding to one of the relatively high code rates and to an untuned circuit including a reactor for limiting the energization of the untuned circuit at said one rate, the improvement of minimizing the possibility of over-energizing the tuned circuit at a lower code rate, comprising the provision on the decoding transformer of a short-circuited turn and the reduction in size of the limiting reactor in the untuned circuit, for limiting the energization of the untuned circuit jointly by the reactor and shorted turn and reducing the power required to be supplied to the untuned circuit from the transformer, whereby to avoid overenergizing the said tuned circuit at the lower code rate should an open-circuit condition exist in said untuned circuit.

LESLIE R. ALLISON.
